UNITED STATES PATENT OFFICE.

LAURENCE E. JONES, OF BRIDGEPORT, TEXAS.

LACE-RACK.

1,074,796.

Specification of Letters Patent.

Patented Oct. 7, 1913.

Application filed August 3, 1912. Serial No. 713,183.

To all whom it may concern:

Be it known that I, LAURENCE E. JONES, a citizen of the United States, residing at Bridgeport, in the county of Wise and State of Texas, have invented certain new and useful Improvements in Lace-Racks, of which the following is a specification.

This invention relates to lace racks.

One object is to provide a lace rack embodying among other characteristics means whereby lace boards may be expeditiously and systematically filed away and readily located when desired so as to obviate loss of time in handling the lace goods when displaying the same to the public in stores and other places.

Any method of filing away the lace boards with the lace thereon may be followed in the use of my improved rack but one object of the invention resides in the provision of a rack embodying a plurality of compartments in which the lace boards may be filed systematically and readily removed from the rack.

Another object resides in the provision of a slideable rack whose base may be fastened or movably mounted on a counter or in a cabinet with means provided whereby the slideable movement of the rack may be easily and readily effected without danger of the rack becoming displaced with relation to its base or from becoming laterally shifted off of the tracks over which it is preferably adapted to slide.

With the above and other objects in view the present invention consists in the combination and arrangement of parts herein-after more fully described, illustrated in the accompanying drawings, and particularly pointed out in the appended claims, it being understood that changes may be made in the form, proportion, size and minor details without departing from the spirit or sacrificing any of the advantages of the invention.

In the drawings: Figure 1 is a side elevation of the invention illustrating its base in section with dotted lines showing the position of the rack in its outermost position. Fig. 2 is a front elevation of the invention.

Fig. 3 is an enlarged detail sectional view illustrating the track and roller connection between the rack and its base. Fig. 4 is a detailed face view of one of the card boards preferably used by me.

Referring now more particularly to the accompanying drawings, the reference char-

acter A indicates a base board including sides 10 which are connected at their ends by the end members 11 and 12 and which has formed preferably at each corner an aperture 13 through which any suitable fastenings (not shown) may be passed for securing the base A fixedly to a counter, shelf or other suitable support.

Mounted in any suitable manner on the side sills 10 of the base A are spaced parallel tracks 14 for a purpose presently explained and secured in any suitable manner to the outer side faces of the side sills 10 are metallic or other plates 15 which have their upper edges bent to form flanges 16 disposed in spaced relation to the base of the plate 15 so as to form channels 17 for a purpose presently explained.

On the base just described I provide a carriage body B on which I provide a suitable lace rack. The carriage body preferably consists of side sills 18 and front and rear connecting pieces 19 and 20, there being brackets 21 preferably secured to the under sides of the side sills 18 in which are journaled rollers 22 adapted to ride upon the tracks 14 on the base A. These brackets 21 preferably extend downwardly below the rollers or wheels 22 so that their lower ends 23 may engage upon opposite sides of the tracks 14 to prevent the wheels or rollers 22 from becoming displaced laterally with respect to the tracks 14 and whereby a true sliding movement of the carriage B on the tracks 14 is insured. To further aid in maintaining a true sliding movement of the carriage and to prevent lateral displacement thereof with relation to the tracks 14, I preferably mount in suitable boxings 23, at the rear end of the carriage B, rollers 24 which are adapted to roll against the under edge of the flange portion 16 of the side plates 15, the boxings 23 each having a projecting portion 25 extending upwardly into the channels 17, and whereby a free and easy movement of the carriage is facilitated and the brackets 21 reinforced in the matter of preventing lateral displacement of the carriage with relation to the tracks 14 on the base A.

On the carriage B I provide a plurality of separate rack compartments into which may be inserted the card boards C on which laces of various colors and designs may be wound in any suitable manner and into which compartments the lace boards with the lace thereon may be systematically

filed away in accordance with any predetermined system or method of filing. In the present instance the plurality of compartments, there being nineteen 5 more or less, is formed between spaced elements D which may be in the form of wires having slightly upwardly inclined legs 26 secured in any suitable manner to side sills 18 of the carriage with 10 their upper ends curved inwardly, as indicated at 27, and from their curved inwardly directed portions, converging downwardly and united into a bight portion 28 which bight portion is arranged preferably to engage 15 the lace boards C intermediate the side edges thereof and slightly below the center of the boards. The legs 26 aside from being inclined inwardly and upwardly, are also preferably inclined slightly forwardly 20 of the carriage, as shown. To prevent side-wise movement of the boards out of their compartments, I preferably provide side rails 29 having legs 30 at their ends which are preferably connected in any suitable 25 manner to the side rails 14 adjacent the end partition members D.

As has been intimated, the base A may be secured fixedly or removably to a counter or other support and it will also be understood 30 that the base A and the carriage may be mounted in a suitable cabinet, there being a portion of a cabinet E shown in Fig. 2 to illustrate one manner in which the device may be mounted in a cabinet. Cabinets 35 having glass backs might be liable to breakage upon an inward sliding movement of the carriage and to avoid danger of breaking glass backs or injuring wood or other backs of cabinets, I preferably secure stops 40 31 in any suitable manner to the rear cross piece 12 of the base A so that inward movement of the carriage is limited by these stops 31.

Under certain conditions it may be preferable 45 to lock the carriage against outward movement of the cabinet or against outward movement with relation to the base A whether it be mounted in a cabinet or on a counter and for this purpose I provide a latch 32 which is preferably pivoted so that 50 it may be thrown into and out of the path of the inner edge of the rear cross piece 20 of the carriage.

To prevent the carriage from becoming 55 disconnected from the base A upon pulling the carriage outwardly off of the base whether the base be mounted in a cabinet or upon a counter or other support, I provide a stop 33' which I secure preferably to the 60 inner side of one of the side sills 10 of the base A so that the stop 33' may be engaged by the inner edge of the cross piece 20 of the carriage for the purpose of limiting the outward sliding movement of the latter.

65 For instance, if the carriage be slid on its

tracks 14 of the base A to the dotted line position shown in Fig. 1 the front wheels or rollers 22 would ride off of the tracks 14 and some means would be provided to prevent the carriage from entirely leaving the 70 tracks, because in such an event, there would be danger of the carriage falling off its base and, aside from the possibility of breaking the carriage, there would be danger of dislodging the lace boards C from their compartments on the carriage. It is for this 75 purpose that I provide a stop 33' and the latter is so positioned as to stop the outward movement of the carriage before the rear rollers or wheels 22 leave the tracks 14. 80 The rear pairs of rollers or wheels 22 are preferably arranged close together so as to maintain the carriage in a true horizontal position when the carriage is pulled out to its outermost limit irrespective of the front 85 rollers or wheels 22 having left the tracks 14. To facilitate this inward and outward sliding movement of the carriage B I preferably provide the same with a hand piece 34 which is preferably secured to or formed 90 with the front connecting piece 19 of the carriage.

While various kinds of lace boards may be employed in carrying out my invention, I have illustrated a form of board preferable 95 to me. For instance, the boards C are preferably provided with the side projections 35 and the intermediate projections 36 by virtue of which latter two different kinds of laces may be readily wound upon a single 100 board. It is preferable, too, to reinforce these projections 35-36 by means of thin metallic or other reinforce 37, whereby the corners of the board or its projections are shielded from unnecessary or undue wear in 105 handling the same.

What is claimed is:—

1. A device of the character described including in combination a base provided with tracks, a carriage provided with wheels for sliding movement along the tracks, means for limiting the inward movement of the carriage, means for limiting outward movement of the carriage, boxings carried by the sides of the carriage, each boxing having an upwardly directed projection, a roller mounted in each boxing, plates carried by the base and at their upper ends provided with inwardly directed flanges for engagement with said rollers of the boxings and to form a channel into which the projections of the boxings project, and whereby sidewise movement of the carriage is prevented.

2. A device of the character described including in combination a base provided with tracks, plates secured to the base and having their upper edges bent upon themselves to provide flanges in spaced relation to the bodies of the plates and forming spaces between the flanges and the bodies of the 13

plates, a carriage provided with wheels for sliding movement along the tracks, boxings secured to the carriage, each boxing having a portion projecting into the space between the flanges and the bodies of said plates, and rollers carried by the boxings for engagement with the flanges of said plates.

3. A device of the character described including in combination, a base provided with tracks, a carriage including side sills and end pieces connecting the side sills and provided with wheels for sliding movement along the tracks, means for limiting the inward movement of the carriage, a latch secured to the base for engagement by the rear connecting piece of the carriage to limit

outward movement of the latter, means for preventing sidewise movement of the carriage off of the tracks, and a latch pivotally secured to the rear portion of the base for 20 swinging movement to permit sliding of the carriage when in one position and also movable to a position to engage the inner side of the rear connecting piece of the carriage to lock the carriage against outward movement 25 when in its rearward position.

In testimony whereof I affix my signature in presence of two witnesses.

LAURENCE E. JONES.
